UNITED STATES PATENT OFFICE.

JULES HENRI DE SIBOUR, OF WASHINGTON, DISTRICT OF COLUMBIA.

DESIGN FOR A HATBAND.

54,812.

Specification for Design.

Patented Mar. 30, 1920.

Application filed February 20, 1920. Serial No. 360,162. Term of patent 14 years.

To all whom it may concern:

Be it known that I, JULES HENRI DE SIBOUR, a citizen of the United States, residing at the city of Washington, in the District of Columbia, have invented a certain new, original and ornamental Design for Hatbands, of which the following is a description, reference being had to the accompanying drawing, forming a part thereof.

The figure represents a side view of the hat band embodying my new design, emblematic of the American Legion.

The hat band comprises a black band and bow having three stripes thereon; the inner stripe being blue and the outer stripes green and khaki brown, respectively, as shown in the drawing.

I claim:

The ornamental design for a hatband, as shown.

In testimony whereof I affix my signature.

JULES HENRI DE SIBOUR.
